UNITED STATES PATENT OFFICE

2,055,551

CALCULATING MACHINE

Robert L. Muller, Detroit, Mich., assignor to Burroughs Adding Machine Company, Detroit, Mich., a corporation of Michigan

Application June 11, 1934, Serial No. 729,967
Renewed December 16, 1935

12 Claims. (Cl. 197—128)

The invention relates to paper feeding equipment for accounting machines, more particularly to front feed mechanisms.

In certain types of accounting machines, such as the "Burroughs Moon-Hopkins" billing machine, it is desirable to make two or more printed records such as a record sheet; on which may be recorded the entries of a number of customers' accounts, for example, all the entries on all customers' accounts for a given month; individual ledger sheets for each customer upon which these amounts may be entered; and a bill or statement; all of which may be made out at the same time, together with such copies as are necessary in the accounting system used. These individual ledger sheets and accompanying papers often differ in width from each other and from the record sheets.

It is necessary to have some simple and easy way of feeding the sheets into the machine and aligning them both with respect to the record or journal sheet and with respect to the individual sheets themselves. The aligning or collating of the smaller sheets must be done without disturbing the record sheet on which the entries should appear in proper spaced relation.

The general object of this invention is to provide an improved feeding equipment which permits ready insertion and alignment of the papers in an accounting machine.

A further object is to provide means whereby the aligning of the papers may be accomplished without the use of special indicating or collating marks.

Another object is to provide a paper feed and alignment equipment in which papers can be inserted from the front of the machine and aligned while in vertical position in which position the printing upon the paper is visible to the operator.

Other objects and their resultant advantages will be apparent from the following specification and drawings which disclose one illustrative embodiment of the invention and in which

Figure 1 is a right side sectional view taken approximately through the center of the paper carriage of a Burroughs Moon-Hopkins machine having the present invention applied thereto and illustrating the machine with the platen tilted back out of printing position and with the feeding and aligning table in horizontal position ready to receive one or more sheets or cards from the front of the machine.

Fig. 2 is a perspective view of the paper carriage and associated parts with certain elements cut away to show the aligning table which has

been moved against the platen in order to position the sheets carried thereby in vertical position where the printing thereon may be visible to the operator.

Fig. 3 is a right side sectional view with the aligning table against the platen and with the papers supported by the table properly aligned and gripped by the feed rolls.

Fig. 4 is a right side sectional view similar to Fig. 3 with the platen lowered to printing position.

The present invention is shown applied to a "Burroughs Moon-Hopkins" billing machine of the type shown in the Hopkins Patent 1,336,904 and is an improvement of the front-feed aligning device shown and described in the Muller Patent 1,774,287.

In the latter patent there is shown an aligning table at the front of the paper carriage. The table is normally positioned horizontally and the ledger sheets may be inserted from the front, bottom end foremost so that the sheets will pass under the platen and between the platen and the feed rolls when the latter are in open position. Alignment of the ledger sheets is obtained by means of collating marks upon the backs of the sheets, it being understood, of course, that the sheets are inserted in the table face down, that is, with the printing record down.

The transactions entered upon the ledger sheets do not always extend to the margin of the ledger sheets, that is, the last printed item on the ledger sheet does not appear close to the right-hand margin of the form for which reason and others, it is sometimes desirable to be able to align the sheets from the front or face thereof where the full printed record may be observed. The present invention makes this possible, that is, the operator may align the ledger sheets when the latter are in full view and the entire record visible to the operator.

Referring to the drawings, the upper portion (Fig. 1) of the machine frame supports transverse guides 2 having raceways in their upper edges for receiving ball bearings 3 upon which corresponding guides 4 of the traveling paper carriage travel. Secured to the guides 4 are the end plates 5 of the paper carriage which is stepped across the machine transversely on the guides. A platen feeding mechanism is also provided for automatically advancing the platen as is shown and described in the Hopkins and Muller patents, to which reference is made for details of construction.

The carriage supports a platen P journaled on

5 a shaft 10 carried by side plates 11 pivoted on a shaft 12 connected by link 13 to a shaft 14 journaled in the side plates 5. This mounting permits the platen to be swung forward and upwardly by means of a handle 15 from the position shown in Fig. 4 to the position shown in Fig. 1. When raised the platen normally occupies the position shown in Fig. 1 in which position it is retained until released and moved to printing position by engagement of a stud 16 in notch 17 in the plates 18 carried by the carriage frame 5. When raised, the carriage exposes the printing line on the platen so that it may be observed by the operator and also permits insertion of the desired forms.

10 The record or journal sheet J is fed under the platen from the rear as illustrated in Fig. 1, passed over a guide rod 21 carried by arms 22 of the platen side plates 11, and fed around and over the platen P as illustrated. Spring guide bands 23 are provided for guiding and holding the journal sheet in position. These bands which are bent around the guide rod 21, extend around the platen and are bent around a cross rod 24 mounted in arms 25 of the side plates 11. The number of record sheets used may be varied to suit the requirements, the drawings show one sheet only and it is understood that the necessary carbon sheets will be used when more than one printed sheet is desired. The spring bands 23 are arranged at the ends of the platen and enable the journal sheet to be retained and spaced with the platen while the ledger sheets are inserted and removed for the printing of individual transactions as will later be explained.

15 The sheets are held in engagement with the platen by feed or pressure rolls 30 which hold the journal sheet or sheets in contact with the platen as it is rotated step by step during operation of the machine causing the sheet to be stepped forward and which cooperate with the platen to form a front feed throat. One or more of these rollers are provided and are carried by a shaft 31 supported in movable plates 32 carried by cross shaft 33. The left-hand plate 32 has an operating handle or finger piece 34 by means of which the feed rollers are moved into and out of engagement with the platen, that is from closed to open throat position. Depressing the finger piece 34 causes 20 the plates 32 to rock counterclockwise to move the rollers away from the platen. The foregoing construction is substantially the same as that shown in the Muller Patent 1,774,287 to which reference is made for further details.

25 The handle and the rollers may be latched in open throat position away from the platen by a latch 35 pivoted on the arm or finger piece 34 and having a shoulder 36 which engages a stud 37 on arm 25 to hold the feed rolls in open throat position. The pressure rolls may be released to grip the papers about the platen or to closed throat position by moving the latch 35 about its pivot, that is, relatively to finger piece 34.

30 As previously stated, it is desirable at times to feed one or more separate ledger or work sheets into the machine from the front and of course provision must be made to align these separate work sheets both relatively to themselves and to the journal sheets without disturbing the journal sheet. This invention provides for this and furthermore, makes it possible to align the separate sheets while they are in vertical and visible position with the printing thereon to the front.

35 For this purpose a paper table or chute is provided which is movable from substantially hori-

zontal sheet-receiving position to substantially vertical position in which latter position the sheet or sheets therein may be aligned after which the table is returned to horizontal position which position it occupies during printing operations. The table consists of a plate 41 (Figs. 1 and 2) which extends for a considerable width of the carriage and is supported by end plates 42 pivoted at 43 to brackets 44 which may be slidably adjusted along the front rail 4 of the carriage in order to adjust the table laterally to any desired position. The table is normally urged in counterclockwise direction about pivot 43 by means of torsional springs 45 (Fig. 2) until the end plates are limited by engagement of a shoulder 46 thereof with a front rail 4 as shown in Fig. 1. Square cross shafts 47 (Fig. 2) are provided to strengthen and add rigidity to the table construction. Right and left paper guides 48 adjustably secured to shaft 47 to accommodate different sized ledger sheets or cards are also provided.

40 With the platen in raised position and the paper table in horizontal position as shown in Fig. 1, the ledger sheets or cards L can be inserted on the table between the two guides 48 and slid rearward until the lower edge passes between platen P and feed rolls 30 which are in open throat position. A shield 51 serves to guide the rear edge of the ledger until it is supported by the stationary frame 52 at the back of the carriage. It will be understood that the ledger sheet is inserted face downward and that the printed figures on the ledger sheet are therefore invisible making it impossible for the operator to align the ledger or collate it to a definite printing position. The ledger sheet or sheets are therefore merely moved to an approximate position, i. e., until the lower edge of the ledger passes between the platen and the feed rolls 30. The paper table may then be moved manually clockwise from its Fig. 1 or 45 horizontal sheet-receiving position to the Fig. 2 position. This movement of the table carries the ledger sheet around the platen until the upper portion of the ledger sheet is substantially vertical.

45 The table is held in this position by means of pointed spring detents 53 located on each stationary bracket 44, and positioned to engage studs 54 projecting from each end plate 42 of the paper table when the table 30 is moved manually in a clockwise direction from Fig. 1 to Fig. 2 position.

50 With the table and ledger sheets carried thereby supported in vertical position as shown in Fig. 2 and with the feed rolls 30 still in open-throat position, the ledger sheets may be manually aligned or collated with the printing thereon in full view of the operator which makes it possible to accurately align the ledger sheets both relatively to the printing line and to the journal sheet. A roller 55 carried by each end of the upper shaft 55 47 engages the platen and insures sufficient room between the table and the platen to enable the ledger sheet to be easily moved to the desired position.

55 To determine the printing line or position of the ledger sheets more readily the table is provided with an elongated opening 60 (Fig. 2). This opening is of sufficient size to permit observation of one complete line of printing, i. e., one complete transaction for the entire width of the ledger. The right side guide 48 is also provided with a corresponding opening 61 so that the printing on the ledger sheet at the right edge may be observed without interruption.

60 In operation the ledger sheet is first moved up- 75

wardly until all items appear above the table 31 after which the ledger sheet is lowered until the last printed transaction can be observed through the opening 60 in the paper table. This opening 5 is in the proper location so that if the last printed transaction appears in the opening the next transaction will be printed directly under or in the next line spaced position relatively to the transaction appearing in the opening when the platen 10 is lowered to printing position.

If desired, greater accuracy of alignment of the ledger forms may be obtained by the use of a plate 63 adjustably secured to the inside of plate 41 by stud and slot connections 64. Plate 63 is positioned with its upper edge visible through the openings 60 and 61. With such a plate the operator aligns the ledger to the top edge of this adjustable plate rather than to the opening itself. Plate 63 is also located slightly closer to the 20 platen than the opening and serves to hold the ledger sheet against the platen which further increases the possible accuracy of alignment, particularly as to an exact horizontal position of the paper. The adjustable plate also provides for adjustment 25 justability to accommodate for different line spacing.

After the ledger has been inserted in the carriage by being positioned on plate or table 40 and the table has been raised to permit alignment of 30 the ledger with the feed rolls in open-throat position, the feed rolls are released to engage the platen and grip the ledger as well as the journal sheet thereagainst. With the ledger and journal thus held in correct position, the platen with 35 its feed rolls is lowered to printing position as shown in Fig. 4. During this counterclockwise movement of the platen and its supporting frame the paper table 40 is cammed in a counterclockwise direction by engagement of the platen with 40 rollers 55 and 66 located at each end of the shafts 47 and rollers 67 carried by end plates 42. This camming of the table by engagement of the platen with the rollers 55, 66 and 67 causes the 45 studs 54 to pass over detent 53 and permits the torsion spring to return the table 40 to horizontal position as shown in Fig. 4. The rollers 55, 66 and 67 in addition to camming the table back to horizontal position, also prevent the platen from smudging the ledger sheet by contact therewith 50 during the time the platen is lowered to printing position.

When the platen is fully lowered to printing position auxiliary feed rolls 70 carried by brackets 71 also slidably adjusted to rail 4 engage the 55 forward portion of the ledger sheet and retain it in close relation to the platen to prevent it from bulging or contacting with the ribbon. With the platen, journal sheet and ledger properly positioned, the machine is operated in the 60 usual manner causing the type T (Fig. 4) to be driven by hammers H to type against the platen P and make the printed impressions upon the ledger sheet or sheets and through the necessary carbon papers, a duplicate impression upon 65 journal J. After the desired entries have been made the platen is raised from printing position, and the ledger is removed. The journal sheet remains in spaced relation with the platen.

An auxiliary table 80 is secured to the rearward edge plate 41 to prevent the forward edge 70 of the ledger card from passing under the table as the platen is raised from printing position. This possibility would occur when the ledger sheet is moved or positioned rearwardly to print 75 near the top thereof. In this position if it were

not for the auxiliary table 80 it would be possible for the upper edge of the ledger sheet to engage the plate 41 as the platen is raised from horizontal to vertical position.

From the foregoing description it will be apparent that a front feed mechanism has been provided in which ledger sheets may be fed from the front and aligned regardless of where the last printed item occurs because the sheets are aligned while the last printing line of the entire 10 width of the sheet is in view of the operator. Furthermore, it is possible for the operator to observe the old balance on the ledger after it is inserted and aligned and then enter the old 15 balance in the keys of the machine before the table is returned to horizontal position. Other advantages such as the elimination of aligning mirrors resulting from the foregoing construction will be apparent to those skilled in the art to whom it will also be obvious that minor 20 changes may be made in the details of construction without departing from the spirit and scope of the invention as defined in the appended claims.

25

I claim:

1. A front-feed machine of the class described having a platen, feed rolls cooperating with said platen to form a front-feed throat, said platen being movable from front-feed position to printing position and said rolls being movable to open 30 and closed throat position, a normally horizontal front-feed paper table for guiding work sheets from front-feed position relatively to said platen into said open throat, said table being movable from substantially horizontal work sheet receiving 35 position to substantially vertical aligning position and vice versa and means operable upon movement of said platen from front-feed position to printing position to move said table from substantially vertical position to work sheet receiving 40 position.

2. A front-feed machine of the class described having a platen, feed rolls cooperating with said platen to form a front-feed throat, said platen being movable from front-feed position to printing 45 position, a pivoted front-feed paper table for guiding work sheets from front-feed position relatively to said platen into said throat, said table being movable from substantially vertical position to a work sheet receiving position and 50 vice versa and means operable upon movement of said platen from front-feed position to printing position to move said table from substantially vertical position to work sheet receiving position, said paper table having an elongated opening 55 therethrough extending substantially its entire width and disposed at a predetermined height relatively to said platen whereby the work sheets may be aligned with said table in substantially vertical position.

3. A front-feed machine of the class described having a printing mechanism, adapted to print along a printing line, a platen movable from printing position relative to said printing mechanism to a front-feed position and vice versa, 65 front-feed means for receiving and holding a work sheet in front-fed position relative to said platen, said front-feed means being movable from a closed to an open-throat position and vice versa, a combination front-feed paper table 70 and line finder in front of said platen, said table being operable, when in sheet-receiving position, to guide a work sheet under said platen and into said open front-feed throat while the platen is 75 in front-feed position and being movable, inde-

closed to an open-throat position and vice versa, said feed rolls also being movable with said platen as the latter is moved from printing to front-feed position, a combination front-feed paper table and line finder in front of said platen, said table being operable, when in sheet-receiving position, to guide a work sheet under said platen and into said open front-feed throat while the platen is in front-feed position and being movable, independently of movements of said platen and after the latter is in front-feed position, to a substantially vertical line-finding position adjacent said platen, said table having means for enabling a work sheet to be aligned with respect to the printing line, means for closing said front-feed throat and moving said platen to printing position, and means automatically moving said front-feed table to sheet-receiving position as the platen is moved to printing position.

10 10. A front-feed machine of the class described having a platen, front-feed means for receiving and holding a work sheet in front-fed position relative to said platen, said front-feed means being movable from closed to open-throat position and vice versa, a front-feed paper chute normally occupying a sheet-receiving position in which it is operable to guide a work sheet into front-fed position while said throat is opened, said chute being movable to a position where it loosely holds said work sheet about said platen with the upper end of said sheet in position to make the front side thereof clearly visible, line finding means on said chute for gauging the line-space position of said work sheet when the same is moved while loosely held, and means operable to close said front-feed throat to tightly grip said work sheet after it is positioned and to cause said chute to be returned to sheet-receiving position.

15 11. A front-feed machine of the class described having a platen, front-feed means for receiving and holding a work sheet in front-fed position relative to said platen, said front-feed means being movable from a closed to an open-throat po-

sition and vice versa, a front-feed paper chute normally occupying a sheet-receiving position in which it is operable to guide a work sheet into front-fed position relative to said platen while said front-feed throat is open, said chute being movable to a position to loosely hold said sheet about said platen with the upper end of the sheet in position to make the front side thereof clearly visible, line finding means on said chute for gauging the line-space position to said sheet when the same is moved while loosely held, means operable to close said front-feed throat to tightly grip said sheet while it is loosely held by said chute, means operable to return said chute to sheet-receiving position, and means operating automatically to hold the front end of said work sheet in substantially vertical position when said sheet is released by said chute.

20 12. A front-feed machine of the class described having a printing mechanism, a platen movable from a printing position relative to said mechanism to a front-feed position and vice versa, front-feed means for receiving and holding a work sheet in front-fed position relative to said platen, said front-feed means being movable from closed to open-throat position and vice versa, a front-feed paper chute normally occupying a sheet-receiving position in which it is operable to guide a work sheet into front-fed position relative to said platen while the latter is in front-feed position and said front-feed throat is open, said chute being movable to a position to loosely hold said work sheet about said platen with the upper end of said sheet in position to make the front side thereof clearly visible, line finding means on said chute for gauging the line-space position of said sheet when the same is moved while loosely held, means operable to return said platen to printing position, and means operating automatically as an incident of the return of said platen for moving said chute to sheet-receiving position.

ROBERT L. MULLER.
